HIS ATTORNEY.

UNITED STATES PATENT OFFICE

EUGENE BULL, OF LOS ANGELES, CALIFORNIA

STROPPING DEVICE

Application filed December 9, 1931. Serial No. 579,910.

My invention relates to improvements in stropping devices for stropping razor blades of various "safety razor" types, wherein a frame for holding and guiding a strop for longitudinal movement therethrough operates in conjunction with means for automatically holding a blade to be sharpened transversely inclined or obliquely to said strop, and also for automatically reversing 5 or turning over said blade and holding the same in a reverse angle, whereby both sides of the edge of a blade may be stropped obliquely to said edge when said frame is reciprocated longitudinally upon said strop. 10 The primary object of the present invention is to provide a new and improved stropping device for "safety razor" blades.

Another object is to provide an improved stropping device having improved means for holding a safety razor blade with its edge inclined transversely to said strop as said blade is moved longitudinally on said strop.

A further object of the present invention is to provide an improved device of the character described having improved means for automatically reversing or turning over the blade to a similar reverse angle when said stropping device is moved in an opposite direction.

A still further object is to provide guide rollers for offsetting said strop to an inclined position relatively to the plane of said blade whereby the edge thereof may be properly engaged by said strop.

A still further object is to provide a new and improved stropping device for engaging and retaining various types of single and double edged blades, as well as perforate and imperforate blades, and for holding the same at an angle, transversely to the strop, and for turning said blades over whereby both sides of the edges thereof may be effectively stropped.

I accomplish these and other objects by means of the improved device disclosed in the drawing forming a part of the present application, wherein like characters of reference are used to designate similar parts throughout the specification and drawing, 50 and in which—

Fig. 1 is a plan view of my improved device disclosing the position of the blade holder when the device is moved in the direction indicated by the arrow;

Fig. 2 is a similar device disclosing the 55 position of the blade holder when the direction of movement of said device is reversed, the said holder being disclosed in dotted lines to disclose mechanism beneath;

Fig. 3 is a side elevation of Fig. 1;

Fig. 4 is a side elevation of the opposite side of the device;

Fig. 5 is an enlarged broken longitudinal sectional view of the device in operation 65 as taken on line 5—5 of Fig. 1 in the direction indicated;

Fig. 6 is an end elevation of Fig. 3;

Fig. 7 is a detailed view of the blade holder disclosing the manner in which a 70 blade of the Gillette-type is held therein; and

Fig. 8 is an enlarged sectional view taken on line 8—8 of Fig. 7, in the direction indicated, illustrating the yieldable means for 75 engaging and retaining a blade of the Gillette-type.

Referring to the drawing, the numeral 1 is used to designate in general what I term 80 a frame provided with oppositely positioned longitudinal slots 2 within which are slidably mounted a pair of parallel rollers 3 connected at their opposite ends by suitable plates 4 and 4'.

The rollers 3 extend transversely of said frame 1 and are provided at their ends adjacent the connecting plate 4' with gears 6 which do not mesh with each other but which mesh with a gear 7 upon a pintle 8 whose ends are pivotally connected to the 90 upper portion of the connecting plate 4' and to a projection 9 upon the opposite side of the frame 1, as disclosed in Figs. 1, 2 and 3 of the drawing. The ends of the pintle 8 are pivotally connected to the upper 95 portion of the connecting plate 4' and the projection 9 by making a hole or bearing in said members slightly larger than the ends of said pintle 8. This will provide a pivotal or universal joint giving sufficient 100

universal or pivotal movement for the required purpose.

A blade holder 11 comprises a pair of hinged leaves mounted upon the pintle 8, 5 one of said leaves being fixed and the other rotatably mounted upon said pintle 8.

The leaves are detachably held in engaging relation with each other, to hold a blade 12, by means of slidably mounted U-shaped 10 members 14 as illustrated in Figs. 1, 7 and 8 of the drawing. One of said hinged leaves is also provided with a yielding retaining device for certain types of perforated blades, such as the Gillette-type, illustrated in dotted lines in Fig. 7 of the drawing. This 15 yielding retaining device comprising preferably a flat spring 16 secured at its approximate center to one hinge of the holder and having its ends bent at right angles to form extensions 17 passing thru aligned apertures 18 within both leaves of said holder 11 and engaging the apertures 19 of a Gillette-type 20 blade 21, held between said leaves, as disclosed in Fig. 7 of the drawing.

The frame 1 is provided at its ends with oblique guide rollers 22 which are arranged at opposite angles to each other and adjacent opposite ends of said frame 1, said 30 rollers 22 being positioned above the rollers 3 so as to offset a strop 23, which passes under the rollers 3 and over the rollers 22, to provide inclined portions of said strop to engage the beveled edge of a blade 12 35 within the horizontally positioned blade holder 11, as disclosed in Fig. 5 of the drawing.

A handle 24 is loosely mounted at its upper end to a transverse member or portion 40 of the frame 1, as disclosed in Fig. 5 of the drawing, which handle is provided to move the frame 1 longitudinally of the strop 23, and the loose connection is provided so that the frame 1 may be automatically adjusted 45 to proper position upon said strop, thereby preventing a too rigid mis-positioned grip of the operator on said handle 24 from mis-aligning the device during the stropping operation.

50 In operation, the strop 23 is threaded thru the frame 1, said strop passing over the end guide rollers 22 and under the connected parallel rollers 3, as disclosed in Fig. 5 of the drawing.

55 The U-shaped clamping members 14 are drawn outwardly as disclosed in dotted lines in Fig. 7 and in full lines in Fig. 8 of the drawing, thereby readily permitting separation and opening of the hinged leaves of 60 the blade holder 11.

If a blade 21 of the Gillette-type is to be stropped, said blade 21 is placed between said leaves with the apertures 19 thereof embracing the extensions 17 of the spring 16, 65 which will prevent said blade from mov-

ing within said holder when the same is closed.

If any type of imperforate blade 12 is to be stropped, the same is placed in proper position within the holder, or between said hinged leaves, and when said leaves are closed the ends of the extensions 17 of said spring 16 are engaged by said imperforate blade 12 and sprung outwardly when said leaves are closed upon said blade and secured in such closed position by pushing inwardly the U-shaped clamping members 14.

70 When the frame 1 is moved, by means of the handle 24, in the direction indicated by the arrow in Fig. 5 of the drawing, the frictional engagement of the strop 23 with the rollers 3 will move said rollers 3 to the rear ends of the slots 2 of the frame 1, as indicated in said Fig. 5. As the pintle is connected at its geared end to the rollers 3 and 75 gears 6 thereon by means of the connecting plate 4', and pivotally connected at its opposite end to the frame 1, the blade holder 11 will be moved to an inclined or oblique 80 position transversely of the strop 23, which 90 position is indicated in Fig. 1 of the drawing.

85 As the blade 12 is thus held obliquely to the strop 23 in its longitudinal movement across said strop, said blade will be obliquely stropped. The frictional engagement of the strop 23 with the rollers 3 during such stroke will tend to rotate the rollers 3, gears 6 and 7, and thereby the blade holder 11, in a direction which will tend to press the beveled edge of said blade 12 against the inclined portion of said strop which is offset by the relation of the guide rollers 22 to the rollers 3, as disclosed in Fig. 5 of the drawing.

95 When the frame 1 reaches the end of the stroke, the same is moved in an opposite direction whereby the frictional engagement of the strop with the rollers 3 will cause said 100 rollers 3, gears 6 thereon and the gear 7, and pintle 8, to reverse or turn over the said holder 11 so that the opposite side of the edge of said blade will be presented to the surface of the strop. During the initial portion of the reverse movement the rollers 3 110 will be moved to the opposite ends of the slots 2 which will move the geared end of the pintle 8 to the opposite end of its slot 29, the pivotally mounted opposite end of said 115 pintle 8 remaining substantially stationary. This will cause the blade holder 11 to assume an opposite and equal angle to that assumed during the previous stroke, as indicated in dotted lines in Fig. 2 of the drawing, and the opposite side of the edge of the blade 12 120 will be stropped at an angle opposite to the angle of stropping of the first stroke.

125 This reciprocating movement is repeated until the blade has been completely and efficiently stropped.

Having thus described my invention what I claim as new and desire to secure by Letters Patent is—

1. A stropping device comprising a frame to hold and guide a strop; a blade holder comprising hinged leaves; a pintle connected to one of said leaves and having one end pivotally mounted within said frame and the other end slidable longitudinally within said frame; a pinion mounted upon said slidable end of said pintle; a pair of connected rollers slidably mounted within said frame and operatively connected to the pinion on the pintle, said rollers being actuated by frictional engagement with a strop extending through said frame, when the same is moved longitudinally on said strop, to move the blade holder, and a blade therein, obliquely to said frame and strop and to draw said holder and blade over said strop; and oblique guide rollers mounted within said frame and holding said strop in parallel relation to the edge of a blade within said holder.
  2. A stropping device comprising a frame to hold and guide a strop; a blade holder comprising hinged leaves; a pintle connected to one of said leaves and having one end pivotally mounted within said frame and the other end slidable longitudinally within said frame; a pinion mounted upon said slidable end of said pintle; a pair of connected rollers slidably mounted within said frame and operatively connected to the pinion on the pintle, said rollers being actuated by frictional engagement with a strop extending through said frame, when the same is moved longitudinally on said strop, to move the blade holder, and a blade therein, obliquely to said frame and strop and to draw said holder and blade over said strop; and oblique guide rollers mounted within said frame and holding said strop in parallel relation to the edge of a blade within said holder and inclined with respect to the plane of said blade.
  3. A stropping device comprising a frame to hold and guide a strop; a blade holder comprising hinged leaves; a pintle connected to one of said leaves and having one end pivotally mounted within said frame and the other end slidable longitudinally within said frame; a pinion mounted upon said slidable end of said pintle; a pair of connected rollers slidably mounted within said frame and operatively connected to the pinion on the pintle, said rollers being actuated by frictional engagement with a strop extending through said frame, when the same is moved longitudinally on said strop, to move the blade holder, and a blade therein, obliquely to said frame and strop and to draw said holder and blade over said strop; and oblique guide rollers mounted within said frame and holding said strop in parallel relation to the edge of a blade within said holder.
- to the edge of a blade within said holder and inclined with respect to the plane of said blade; and a handle loosely connected to said frame for moving the same longitudinally along said strop whereby said frame may be automatically adjusted relatively to said strop.
4. A stropping device comprising a frame to hold and guide a strop; a blade holder comprising hinged leaves; a pintle connected to one of said leaves and having one end pivotally mounted within said frame and the other end slidable longitudinally within said frame; a pinion mounted upon said slidable end of said pintle; a pair of connected rollers slidably mounted within said frame and operatively connected to the pinion on the pintle, said rollers being actuated by frictional engagement with a strop extending through said frame, when the same is moved longitudinally on said strop, to move the blade holder, and a blade therein, obliquely to said frame and strop and to draw said holder and blade over said strop; and oblique guide rollers mounted within said frame and holding said strop in parallel relation to the edge of a blade within said holder and inclined with respect to the plane of said blade; a handle loosely connected to said frame for moving the same longitudinally along said strop whereby said frame may be automatically adjusted relatively to said strop; and means for detachably retaining blades of the Gillette-type between the leaves of said holder.

In witness whereof, I hereunto set my signature.

EUGENE BULL.
